UNITED STATES PATENT OFFICE.

EUGENE L. WARNER, OF WAVERLY, KANSAS.

WOVEN-WIRE FENCE FABRIC.

SPECIFICATION forming part of Letters Patent No. 709,065, dated September 16, 1902.

Application filed February 3, 1902. Serial No. 92,455. (No model.)

To all whom it may concern:

Be it known that I, EUGENE L. WARNER, a citizen of the United States, residing at Waverly, in the county of Coffey and State of Kansas, have invented a new and useful Woven-Wire Fence Fabric, of which the following is a specification.

My invention is an improved woven-wire fence fabric composed of running-wires and cross-wires intersecting each other and twisted together at their intersecting points to form meshes of two sizes, the larger meshes alternating with the smaller both longitudinally and transversely of the fabric, and the said running and cross wires being thereby prevented from slipping at their intersecting points and altering the shape of the meshes, as hereinafter fully described and claimed.

The accompanying drawing is a side elevation of a woven-wire fence fabric constructed in accordance with my invention.

In the making of my improved woven-wire fence fabric I employ continuous running-wires *a* and cross-wires *b*. The running-wires are provided with lateral offsets 1 at suitable regular distances apart, which lateral offsets extend alternately in opposite directions. The cross-wires *b* are provided with similar lateral offsets 2 at suitable regular distances apart, which offsets 2 extend also alternately in opposite directions. The running-wires and cross-wires are disposed so that their respective lateral offsets intersect each other, and the said running-wires and cross-wires have their said laterally-offset intersecting portions twisted together, as at 3. Thereby the running and cross wires are so secured together at their intersecting points that they cannot slip upon one another to alter the shape of the meshes and injure the appearance of the fabric. The spaces between the reversely-disposed lateral offsets 2 of the cross-wires *b* are shorter than the corresponding spaces of the running-wires *a* between the reversely-disposed lateral offset portions 1 thereof, and hence the said running and cross wires form meshes A B of rectangular form. The meshes A are larger than the

meshes B, and the larger meshes alternate with the smaller meshes both longitudinally and transversely of the fabric, as shown. The ends of the cross-wires are secured to selvage wires *c* either by coiling the end portions of the cross-wires on the selvage-wires, as here shown, or in any other suitable manner. The said selvage-wires may be either plain or barbed, or one of the selvage-wires may be plain and the other barbed, and I do not wish to be restricted in this particular.

A woven-wire fence fabric thus constructed may be very easily and economically manufactured, is exceedingly strong and durable, preserves the rectangular form of its meshes, and is very sightly.

Having thus described my invention, I claim—

1. A woven-wire fence fabric composed of continuous running-wires, and cross-wires, each offset alternately in opposite directions at the points of intersection, said running and cross wires having their respective offset portions twisted together to form rectangular meshes, substantially as described.

2. A woven-wire fence fabric composed of running-wires and cross-wires, each at suitable regular intervals being bent to form reversely-disposed lateral offsets, the distances between the respective horizontal and respective vertical reaches of the running and cross wires intermediate of the offset portions thereof being varied alternately and the said lateral offsets of said running and cross wires intersecting each other and being twisted together to prevent slipping and to form meshes of two sizes, the larger meshes alternating with the smaller, both longitudinally and transversely of the fabric, substantially as described.

In testimony that I claim the foregoing as my own I have hereto affixed my signature in the presence of two witnesses.

EUGENE L. WARNER.
